UNITED STATES PATENT OFFICE.

ANSON M. HOWARD, OF ENFIELD, MASSACHUSETTS.

VICE.

SPECIFICATION forming part of Letters Patent No. 243,903, dated July 5, 1881.

Application filed January 15, 1881. (Model.)

To all whom it may concern:

Be it known that I, ANSON M. HOWARD, of Enfield, Hampshire county, State of Massachusetts, have invented a new and useful Improvement in Vises, of which the following is a specification.

The object of my invention is to obtain parallel movement of the moving jaw in vises by simple and durable mechanism, which can be readily applied to vises of ordinary construction.

My invention consists in a rack and pinion attachment fitted for operation by the vise-screw, as hereinafter described and claimed.

In the drawings, Figure 1 is a side elevation of a vise containing my improvements, and Fig. 2 is a rear elevation of the same.

Similar letters of reference indicate corresponding parts.

A is a table, the side *a* of which forms the fixed jaw of the vise. *b* is the screw working in the jaw *a*, and *c* is the moving jaw carried by the screw. These parts are of the usual construction.

The guide-arm *d* of the jaw *c* extends, as usual, through an aperture in jaw *a*, and is formed as a rack on its upper side. On the rear end of screw *b* is a loose collar, *e*, and to this collar a rack-bar, *f*, is hung by one end,

such bar *f* extending beneath the screw through

an aperture in jaw *a*, so that the racks *d f* are parallel and move with the jaw *c*.

On the back of the jaw *a* is fixed a plate or box, *g*, that is apertured to receive the center studs of pinions *h h*, which are placed one above another and mesh together and with the racks *d f*, respectively.

In operation, the screw being turned to move the jaw *c*, the rack *f* is moved endwise, and acts through the pinions to give a corresponding movement to rack *f*. The screw thus acts on both ends of jaw *c* at once, and parallel movement is insured.

This mechanism is simple and not liable to get out of order. The parts can be readily applied to ordinary screw-vises, the collar *e* put on the vise-screw and secured by a set-screw tapped into the end of the screw, and the rack-bar *d* substituted for the usual plain bar.

Having thus described my invention, I claim as new and desire to secure by Letters Patent—

In vises, the combination, with the fixed jaw *a*, screw *b*, and movable jaw *c*, of the rack-bars *d f*, collar *e*, plate *g*, and pinions *h h*, as and for the purpose described.

ANSON MERRICK HOWARD.
